UNITED STATES PATENT OFFICE.

MORRIS G. ROSENTHAL, OF CINCINNATI, OHIO, ASSIGNOR OF ONE-HALF TO FRED E. KLEIN, OF CINCINNATI, OHIO.

LAUNDRY TAG.

Application filed April 12, 1922. Serial No. 551,882.

To all whom it may concern:

Be it known that I, MORRIS G. ROSENTHAL, a citizen of the United States, and a resident of Cincinnati, in the county of Hamilton and State of Ohio, have invented certain new and useful Improvements in Laundry Tags, of which the following is a full, clear, and exact description, reference being had to the accompanying drawings, forming 10 part of this specification.

My invention relates to checks or tags for laundry use for marking articles prior to passing them through the laundry to permit subsequent identification.

15 In the past there have been a great number of different forms of identification mark, including printed-up labels, pin tags, clamping tags of metal, stitched-down labels of fabric to receive the mark, and removable 20 stitched-on labels. White articles have usually been marked by printing direct on some inconspicuous corner and dark articles by means of a tag pinned on with a safety pin, but the other forms mentioned have all 25 been used to some extent.

It is the object of my invention to provide a metal tag, thereby insuring permanence to the tag and enabling its re-use. It is my object to arrange this tag so that it 30 may be stitched direct to the fabric, but will be removable either by cutting the threads or by pulling them.

I also provide in connection with the tag for an eyelet or slot by means of which the 35 tag can be hung upon a peg, thus facilitating assorting of other than "flat work" in the laundry.

In connection with the tag I so form it that it is adapted for easy mechanical feeding 40 to a stitching device from a magazine.

Other advantages gained by the use of the metal tag is that it can be made of uniform thickness, thereby providing an easy way of counting by piles of tags. The metal 45 is not affected by starch and cannot run or stain the articles being washed.

These various objects and advantages I accomplish by that certain construction and arrangement of parts to be hereinafter more 50 specifically pointed out and claimed.

In the drawings,

Figure 1 is a plan view showing the tag attached to a garment by a button sewer draw thread stitch.

55 Figure 2 is a sectional view showing the

tag mounted on a piece of fabric in a preferred way.

Figure 3 is a more or less diagrammatic view showing how the tag may be held and discharged from a magazine pin.

Referring to the exact form of tag in the drawings, which it will be understood may be varied through a wide degree, I show the tag or check 1 having at the forward end a pair of holes 2 through which the check 65 is stitched to a garment. In the drawings I have shown a button sewer stitch 3 with a draw thread 4, which engages the various loops forming the stitch.

The body of the tag is formed with a slot 70 5 by means of which the tag may be hung over a peg and somewhere on the face of the tag and on the reverse side also, if desired, will be imprinted the identification mark, such as A—71 (meaning Lot A, number 71).

At the rear of the tag I provide holes 6 from which narrow slots 7 extend to the rear edge of the tag body. By this means the tag is adapted to be set over pins in a magazine 80 or hopper, such as the pins 8. The large portions of the pins will hold the tags slidably, but irremovably, but the bottom tag can be discharged where the pin is made small as at 9, since the slot 7 will provide clearance for movement over said portion 9.

It is important to note that the tag shown is capable of being hopper fed, both from its rectangular or noncircular shape and because of the guide holes 6 and slots 7.

Among other things it is notable that the check or tag is perfectly flat and has no movable parts. Due to its permanence and re-use, the final cost of the tag will be much less than the cost of fabric tags which are 95 thrown away or delivered with the article to the customer and by him removed.

Since the tag has a portion of its body between the stitching holes, any form of stitch may be used and a knife pressed 100 against the threads where they lie across the tag body. With a little practice the tag removal may be done very rapidly in this manner, without any danger to the laundered article. As each article must be checked 105 against the original list before going into the washing machinery and must be packed for transportation, no extra handling is necessary for removal of the tag.

The tags can always be easily found and 110

will not starch down, which cannot be said of stitched-on labels. By the word "metallic" in the claims that follow I wish to include substitutes for metal.

5. Having thus described an exemplary structure illustrating my invention, what I claim as new and desire to secure by Letters Patent, is:—

1. A marking tag for laundry articles, 10 comprising a flat, stiff plate having a central aperture, and a pair of apertures located at one end of the central aperture, said central aperture being adapted for suspension of the tag with the article attached thereto, and the 15 pair of apertures being adapted for receiving stitches, whereby the tag is mounted on an article in the laundry.

2. A laundry marking tag comprising a flat, stiff plate having a central aperture for

suspension of the tag, and a pair of apertures 20 for receiving stitches to mount the tag, and a pair of apertures having a reduced neck, opening to the edge of the tag opposite the pair of apertures, for the purpose described.

3. A laundry marking device comprising 25 in combination with a stiff tag, a pair of apertures therein, and mounting stitches passing across the body of the tag between said two apertures, said stitches adapted to engage a piece of fabric for marking the same 30 with the tag, and the intervening metal serving as an abutment against which the stitches may be cut for quick removal of the tag, and a large aperture in the tag independent of the other apertures and serving 35 as a loop by means of which the tag may be suspended.

MORRIS G. ROSENTHAL.
